[57] CLAIM

The ornamental design for an enclosure for a machine tool, as shown.

DESCRIPTION

FIG. 1 is a left side elevational view of the enclosure for a machine tool embodying my new design, the right side being a mirror image;

FIG. 2 is a front elevational view thereof;

FIG. 3 is a top plan view thereof;

FIG. 4 is a bottom plan view thereof;

FIG. 5 is a perspective view thereof;

FIG. 6 is a rear elevational view thereof;

FIG. 7 is a perspective view thereof, with the door in the open position.

FIG. 1

FIG. 2

FIG. 3

FIG. 4

FIG. 5

FIG. 6

FIG. 7
